UNITED STATES PATENT OFFICE.

CHARLES E. YOUNT, SR., OF HARRISBURG, PENNSYLVANIA.

SUNBONNET.

No. 884,553.

Specification of Letters Patent.

Patented April 14, 1908.

Application filed December 16, 1907. Serial No. 406,677.

To all whom it may concern:

Be it known that I, CHARLES E. YOUNT, Sr., a citizen of the United States of America, and a resident of Harrisburg, in the State of 5 Pennsylvania, have invented a new and useful Improvement in Sunbonnets, of which the following is a specification.

This invention is additional to the improvements in sunbonnets set forth and 10 claimed in my specification forming part of Letters Patent No. 833950 dated October 23 1906, and a second specification forming part of Letters Patent No. 877,029, dated January 21, 1908. In common with said 15 previous improvements the leading objects of the present invention are to adapt the sunbonnet to be effectively laundered before and after use; to adapt the same to be packed flat for storage and shipment, whereby a great 20 saving in paper boxes, wooden packing cases, freight and cartage is effected; to wholly dispense with detachable parts and open seams with their fastenings, and especially with 25 hooks and eyes and the like, so as to avoid the production of rust spots; and to obviate the employment of elastics, which are liable to become permanently inoperative, and are 30 objectionable because of their pressure upon the head.

The leading object which distinguishes the present invention is to provide for securing the advantages above stated in a sunbonnet, the crown portion of which may be made larger to any required extent without correspondingly enlarging the puff portion, and in 35 which the puff portion can be adjusted and shaped independently of the crown portion so as to present a more pleasing appearance and the crown portion may be subsequently 40 adjusted and fitted to the head of the wearer.

Other objects will be set forth in the general description which follows.

A sheet of drawings accompanies this specification as part thereof.

Figure 1 is a face view of the sunbonnet as flattened and folded in packing the same in boxes; Fig. 2 is a face view of the same showing its other face in its flattened condition but unfolded; Figs. 3 and 4 are side views of 45 the sunbonnet showing it respectively as it appears before the adjusting strings of the crown portion are tied, and in the shape in which it is worn; and Fig. 5 is a fragmentary detail view hereinafter mentioned.

Like reference characters refer to like parts in all the figures.

The improved sunbonnet, in common with those set forth in my previous specification, includes a relatively stiff or stiffenable crown portion, *a*, a puff portion, *b*, of relatively soft fabric, and a cape portion, *c*, which may be and preferably is formed in one part with said puff portion. To the rear edge of the crown portion *a*, which is preferably and conveniently straight as shown, 60 the upper edge of the puff portion *b* is stitched fast in a central position after being gathered to give the puff portion the required fullness. At a lower point the puff portion *b* is provided with a transverse draw-string 65 pocket, *d*, and with a draw string, *e*, Fig. 5, within said pocket for gathering the puff more or less at will at that point. This line may determine the upper edge of the cape portion *c* as heretofore, but has no fixed relation to the rear edge of the crown portion *a*, as indicated in Figs. 1 and 2, which enables 70 additional fullness to be thrown into the puff as may be desired.

The drawing string *e* is preferably and 80 conveniently fastened at both ends in this arrangement, and exposed at mid length by an opening, *f*, Fig. 5, in the pocket *d*; but this and other details of construction which are not included in my claim hereto appended 85 are not considered material.

The crown portion *a* when flattened extends laterally beyond the puff portion *b* at both sides, as best shown in Figs. 1 and 2, and a pair of strings, 1 and 2, for adjusting 90 the crown portion are fixedly attached to the rear edges of the laterally projecting ends of the crown portion; these strings being tieable behind the puff portion and so as to mask its draw-string pocket after the crown 95 portion is separately adjusted by means of the draw string *e*. Compare Figs. 3 and 4.

The crown portion *a* may be made with or without an edge ruffle, *g*; means for fastening the bonnet under the chin, consisting 100 preferably of the customary pair of tie strings 3 and 4, are attached to the lateral extremities of the crown portion. Other fastening means may obviously be substituted for such tie strings 3 and 4, and other like modifications will suggest themselves to those skilled 105 in the art.

Having thus described said improvement, I claim as my invention and desire to patent under this specification:

A flattenable sunbonnet including a puff portion of soft fabric permanently gathered

at its upper edge to give it the required fullness and provided at a lower point with a transverse draw-string pocket and with a draw string within said pocket for gathering 5 the puff portion more or less at will at that point, a relatively stiff crown portion to the rear edge of which said gathered upper edge of the puff portion is stitched fast in a central position and which projects laterally at both 10 sides beyond said puff portion when the bonnet is flattened, strings tieable behind

the puff portion to adjust the bonnet to the head attached to the rear edge of the laterally projecting ends of the crown portion, and means for fastening the bonnet beneath 15 the chin attached to the lateral extremities of said crown portion, substantially as hereinbefore specified.

CHARLES E. YOUNT, SR.
